UNITED STATES PATENT OFFICE.

RICHARD H. SEER, OF MILWAUKEE, WISCONSIN.

LAMP REFLECTOR.

Application filed March 16, 1925. Serial No. 15,893.

To all whom it may concern:

Be it known that I, RICHARD H. SEER, a citizen of the United States, and resident of Milwaukee, in the county of Milwaukee, 5 and State of Wisconsin, have invented certain new and useful Improvements in Lamp Reflectors; and I do hereby declare that the following is a full, clear, and exact description thereof.

10 This invention relates to lamp reflectors. Objects of this invention are to provide a lamp reflector which is adapted to be used in connection with pictures, beds, desks or other suitable places, and which is so constructed that it is of attractive and pleasing appearance, and which may be most readily adjusted to throw the light upon the picture, for example, in any desired direction, and which also may be adjusted vertically or laterally with respect to the picture to secure the best results.

15 In devices of this type it has been frequently the case that the lamp socket loosened during use and particularly due to the adjustment of the reflecting hood or shell which gradually unscrewed the socket as the shell was rocked back and forth. Further difficulty has been experienced due to the loosening of the vertical and lateral adjustments as they are usually dependent solely upon the frictional engagement of a single screw.

20 This invention is designed to overcome such defects as those noted above, and further objects of the invention are, therefore, to provide a lamp protector in which the hood or shell may be freely rocked to secure the exact adjustment desired without any possibility of loosening of the lamp socket, and to provide vertical and lateral adjustments which are not dependent merely upon frictional engagement of a screw but are so formed that a very secure, firm, and reliable binding action is attained.

25 An embodiment of the invention is shown in the accompanying drawings, in which:—

Figure 1 is a view showing the reflector in position and with the major portion of the parts in section.

30 Figure 2 is a fragmentary plan view of the structure shown in Figure 1, such view being partly in section.

Figure 3 is a view from the rear side of the reflector showing a part of the reflector

in section together with a part of the supporting arm.

Figure 4 is a sectional view on the line 4—4 of Figure 1.

Figure 5 is a sectional view to an enlarged scale on the line 5—5 of Figure 1.

The reflector is supported by means of a bracket 1 secured to the picture frame 2 or to a suitable support and preferably upon the rear side of such support. This bracket is shown in greater detail in Figure 5 from 65 which it will be seen that it is attached by means of screws 3 passing through apertured ears extending laterally from the bracket. This bracket is provided with a rectangular groove or socket on its inner side which 70 houses the square or rectangular head 4 of a bolt 5, such bolt projecting through a bracket and outwardly therefrom. The rear side of the bracket is provided with a channel 6 having tapered walls for receiving the 75

similarly beveled vertical adjusting and supporting bar 7. This bar is provided with a plurality of elongated apertures 8 through which the bolt 5 passes. A wing nut 9 is used to clamp the bar into wedging engagement with the tapered guideway in the bracket 1, as most clearly shown in Figure 5, and to thus firmly lock the bar in any one of a multitude of adjusted positions, such locking being secured not solely by the 85 binding action of a single screw, but by the cooperative wedging or binding action of the bracket and bar.

80 It is to be noted from Figures 1, 2 and 4 that the upper end of the bar is provided with a transverse rectangular slot 10. This slot 10, it will be noted particularly from Figure 2, is provided with inwardly directed ears 11 which extend approximately half way up the slot. A lock screw 11' is threaded through the upper end of the bar for a purpose hereinafter to appear.

85 The laterally or outwardly projecting arm 12 is of rectangular cross section and is adapted to slide back and forth through the 90 rectangular aperture 10 in the bar 7. It is provided with a plurality of notches 13 contoured to fit the ears 11 of the bar 7, as shown in Figure 2, when the arm 12 is pressed downwardly into the lower portion 95 of the slot 10 by means of the screw 11'.

100 The outer end of the bar 12 is downwardly curved, as indicated at 14 in Figure 1. At

its outer end it is provided with a pair of spaced lugs 15 and with a transverse aperture. These lugs 15 receive between them the upturned portion 16' of a strap 16 and thus securely hold the strap against rocking motion. A bolt or screw 17 is passed through the outer end and through the strap 16 and carries a nut 18 on its inner end. It is to be noted from Figure 1 that the nut 18 is held between the ears 15 and is thus prevented from turning.

The bar 16 constitutes in effect a supporting yoke for the reflector, as most clearly shown in Figures 2 and 3. It is to be noted that the outer ends of the bar 16 are received in suitable channels formed in heads 19. These heads are preferably ornamented, as shown in Figures 2 and 3, and are provided with an ornamental beaded portion 20, such bead, however, is interrupted in its upper part and a pair of lugs or ears 22 are provided which together form the channel for the reception of the end of the bar 16. A screw 23 is passed through each end of the bar 16 and into the appropriate head. The inner end of one of the heads is provided with a flat boss 24 which receives the foot of a bracket 25, such bracket carrying the lamp socket 26 for the electric lamp 27.

It is to be noted particularly from Figure 3 that the heads are provided with circular channels 28. These channels receive the ends of a cylindrical hood 29 of sheet metal and permit free sliding of the hood. It is to be noted from Figures 1 and 3 that the hood 29 has its ends spaced apart to provide a mouth or opening therethrough for the passage of the light. This hood is readily adjusted by rocking it within the circular grooves 28 in the heads 19.

It will thus be seen that a lamp reflector has been provided which may be readily attached to the back of a suitable support such for example as a picture frame, which may be easily and quickly adjusted, vertically or outwardly, with regard to the support, and

which may be locked in a very secure and firm manner without danger of subsequent loosening.

It will further be seen that an extremely simple and practical form of adjusting hood and support therefor is provided and that this hood may be most easily turned to secure the exact lighting desired.

It is to be noted further that this construction lends itself admirably to ornamental and attractive design and to strong and substantial construction with, however, relative cheapness of manufacture.

Although the invention has been described in considerable detail, it is to be understood that the invention may be variously embodied and is, therefore, to be limited only as claimed:

I claim:

A lamp reflector comprising a bracket adapted to be attached to a support, said bracket having a channel formed in its outer face, a vertical rod slidably mounted within said channel, said channel and said rod having cooperating beveled faces, a bolt passing through said bracket and said rod and causing binding of said beveled faces, said rod having a transverse aperture at its upper end provided with inwardly directed ears in its lower portion, a transverse arm slidably mounted within said aperture and having notches adapted to lock with said ears, a screw passing through said bar for holding said arm in engagement with said ears, a yoke carried by the outer end of said arm, heads carried by the outer ends of said yoke, said heads having circular grooves in their opposite faces, a lamp socket supported from one of said heads, and a cylindrical hood having its outer ends slidably mounted within said circular grooves.

In testimony that I claim the foregoing I have hereunto set my hand at Milwaukee, in the county of Milwaukee, and State of Wisconsin.

RICHARD H. SEER.
